RADIO FREQUENCY DISPLAY SIGN

Frank M. Shoemaker, Pittsburgh, Pa.

Application February 26, 1949, Serial No. 78,655

3 Claims. (Cl. 315—206)

1

This invention relates generally to high frequency energized signs or displays and more particularly to a sign or display free of radio and video interference.

High frequency energized signs and displays, employing direct connected or capacity coupling to illuminate the characters, produce an interference detrimental to both radio and video reception. In fact instances have occurred wherein such high frequency energized signs have actually jammed commercial and governmental communications. Again parts of such circuits must be carefully insulated to prevent accidental injury owing to the proximity and the personal interest that such signs and displays are purposely intended, although the illuminated characters may themselves be handled in the proximity of the capacity coupling without injury. The circuits generally employed to energize capacity coupled signs or displays invariably have a low Q which is conducive to high radiation of interfering harmonics whether the frequency generated is below that of broadcast band or is within the video band.

The principal object and advantage of this invention is the provision of a high frequency sign or display wherein the characters are energized by a circuit operating on a fixed selected frequency through a capacity coupling that is not dangerous and provides a high Q circuit that is substantially nil of interference radiation by the elimination of harmonics. This type of circuit permits the choice of an oscillating frequency that is lower than the frequency used in the present capacity coupled high frequency signs and displays, which fact obviously results in a materially less radiation at the selected fundamental frequency.

This invention also contemplates a novel oscillating circuit wherein the plate and load circuits are tuned and the grid circuit is not tuned, although all three parts of the circuit are inductively coupled.

Another object is the provision of an oscillatory circuit employing a high frequency transformer the secondary of which provides the inductance of a closed resonant circuit which is the load circuit and the capacity of which is low and resonates at a selected low frequency of the same order as in the resonant plate circuit, permitting the latter to function with a high Q.

One of the principal distinctions between the novel circuit comprising this invention and that of other oscillating circuits resides in the fact that the present circuit has a tuned and reso-

2

nated plate circuit that is required to produce resonance at a selected low frequency in the load circuit. The use of a low capacity in the resonant load circuit permits the construction of a very simple and economical unshielded capacitive load mat for use in providing the capacity coupling from the resonant load circuit to the gas filled or fluorescent treated characters without radiating interference energy.

10 Other objects and advantages appear hereinafter in the following description and claims.

The accompanying drawings show, for the purpose of exemplification but without limiting the invention or claims thereto, certain practical embodiments of the invention wherein:

Fig. 1 is a circuit diagram comprising this invention wherein the power supply is connected as a shunt feed to the oscillating circuit employing a triode with a radio frequency transformer coupling between the resonant plate circuit and the resonant load circuit.

Fig. 2 is a circuit diagram similar to that of Fig. 1 except the power supply is connected as a series feed to the oscillating circuit employing a pentode.

Fig. 3 is a similar circuit diagram using a shunt fed oscillating circuit employing an auto-type radio frequency transformer coupling between the resonant plate circuit and the resonant load circuit.

Fig. 4 is a similar circuit diagram using a series fed oscillating circuit employing an auto-type radio frequency transformer coupling between the resonant plate circuit and the resonant load circuit.

Fig. 5 is a plan view of the capacitive coupled load mat with some characters indicated thereon.

Fig. 6 is a sectional view of the capacitive coupled load mat shown in Fig. 5.

Referring principally to Fig. 1 of the drawing, the vacuum tube 1 is a triode having the anode 2, the control grid 3, and the indirectly heated cathode 4, the heater of which is not shown. The cathode 4 is connected by wire 5 to the grid blocking resistor 6 and the switch 7 connected in multiple, the other side of which is connected to ground and the negative polarity of a suitable source of high voltage D. C. supply by the wire 8.

50 The positive polarity of the high voltage D. C. supply is connected by the wire 10 to the R. F. by-pass condenser 11 and the R. F. choke 12. The other side of the condenser 11 is connected to ground for the purpose of by-passing the power supply with any radio frequency that may

get through the R. F. choke coil 12. The other end of the coil 12 is connected by the wire 13 to the anode 2 and to the D. C. blocking condenser 14. The other side of the blocking condenser 14 is connected by the wire 15 to the anode tank circuit made up of the inductance 16 and the capacitance 17 which form the plate resonant circuit which must be turned to a selected frequency such as 120 kc. The other side of this plate resonant circuit is connected by 18 to ground.

The grid 3 is connected through the wire 20 to the antiparasitic resistor 21, the other end of which is connected by the wire 22 to one end of the pickup coil 23 that is in turn connected by 24 to the grid leak condenser 25 and the grid leak resistor 26 that are connected in multiple and to the wire 8 that is grounded.

The resonant load circuit consists of the inductance 27 and the capacitance 28, the former having materially more turns and functioning in the manner as a secondary relative to the inductance 16 which functions as a primary of a radio frequency transformer and has materially less number of turns.

One side of the capacitance 28 of the resonant load circuit is connected by the wires 18 and 29 to ground and to one end of the inductance 27, the other end of these resonant elements are connected together by the wire 30.

It is preferable to place each of the inductances 16, 27 and the pickup 23 in alignment on a single form as indicated by their arrangement in the circuit diagram.

The capacitance 28 is in effect an unshielded load mat as illustrated in Figs. 5 and 6 wherein one side of the capacity is formed by a series of electrodes 31, 32 and 33 connected at one end by the strip 34 and the other side is formed by the series of electrodes 35, 36 and 37 connected at the other end of the mat 28 by the strip 38. The leads 29 and 30 may be connected to the respective sides of the capacitance mat at any desired location.

In constructing the mat 28 it has been determined preferable to employ aluminum foil for the strips which are interposed as a stratified layer in the plastic board 40 as shown in Figs. 5 and 6. The plastic making up the board may be of any suitable opaque thermosetting phenol formaldehyde resin or a clear thermoplastic resin such as methyl methacrylate. The latter mat will of course show the foil strips but the cardinal parts of the characters may be discerned from either side of the board. The mating pairs of strips should be placed to provide a properly spaced electrostatic field suitable for the size or dimension of the characters to be employed. The characters as indicated at 41 may be sealed tubes having an inner coating of fluorescent material and supplied with ionizable gas such as mercury vapor, or they may be made of a fritted glass containing fluorescent material and an ionizable gas wherein the fritted glass may be molded into a suitable character.

These characters may be placed on the shelves 42 and rest back against the surface of the mat 40. The shelves hold the characters so that they are properly spaced relative to the corresponding pairs of strips 31 and 35 and the electrostatic field will ionize the gas which in turn causes the fluorescent material to glow and produce illumination. The other shelves 42 are likewise arranged to support characters relative to the other two pairs of electrodes 32, 36 and 33, 75

37. Again this mat may be constructed in different shapes or arranged to support characters of different forms than those indicated.

Referring to Fig. 2 which shows the power supply connected as a series feed to the circuit, the positive polarity of the high voltage D. C. supply is connected by the wire 43 to the by-pass condenser 11, the other side of which is grounded to the screen grid 44, and to the anode tank circuit made up of the inductance 45 and the capacitance 46 which are selected to form the plate resonant circuit that is likewise tuned to a selected supersonic frequency such as 120 kc. The other side of this resonant circuit is connected by the wire 47 to the anode 48 of the pentode 50. The cathode 51 of this pentode is connected by the wire 5 through the cathode keying circuit of the grid blocking resistor 6 and the switch 7 as previously described. The grid 52 is likewise connected by the wire 20 to the same type of grid circuit previously described. The resonant plate tank circuit 45, 46 is not connected directly to the resonant load circuit 27, 28 as high voltage exists between the primary inductance 45 and the secondary inductance 27 but they are preferably wound on the same form and are sufficiently closely arranged to be inductively coupled without causing the resonant plate circuit from arcing to the resonant load circuit.

30. In the circuit of Fig. 3 a shunt feed is used to supply an oscillating circuit employing an R. F. autotype transformer coupling between the resonant plate circuit and the resonant load circuit using the triode 1. The positive polarity of the high voltage D. C. supply is connected by the wire 10 to the R. F. by-pass condenser 11 and the R. F. choke coil 12. The other side of the coil 12 is connected by the wire 13 to the anode 2 and the D. C. blocking condenser 14. The other side of the blocking condenser is connected by the wire 53 to an intermediate point on the inductance coil 54 separating into the inductances 55 and 56, the former being a part of the tank circuit of the resonant plate circuit the capacitance of which is indicated by the condenser 57. The wire 58 connects the R. F. by-pass condenser 11, the other side of the tank circuit 55, 57 and one side of the capacitance 28 to ground. The other side of the latter is connected by the wire 59 to the other end of the inductance 56. Thus the resonant tank circuit and the resonant load circuit both include the inductance section 55 in their circuits which has the effect of reducing the current in this section as the currents of these two resonating circuits flow in opposite directions and thus cancel each other in accordance with their respective magnitude.

The circuit of Fig. 4 is a series fed oscillating circuit employing an R. F. autotype transformer coupling between the resonant plate circuit and the resonant load circuit using the triode 1. The cathode and grid circuits are the same as that of Figs. 1-3 and the positive polarity of the high voltage D. C. supply is connected by the wire 10 to the R. F. by-pass condenser 11, which is grounded on its other side, and one side of the plate tank circuit formed by the capacitance 60 and that portion 55 of the inductance 54. The other side of the resonant plate circuit is connected to the anode 2 by the wire 61. In all other respects the circuit is made as that shown in Fig. 3.

One particular object and advantage in using an autotype R. F. transformer coupling between the resonant plate tank circuit and resonant load

circuit, such as shown in Figs. 3 and 4, resides in the fact that material efficiency will be gained if the capacitance 28 is required to be materially increased, the autotransformer tap may be changed to materially increase the inductance 55 without much change in the total inductance of the whole winding 54. The higher the percentage of the inductance 55 of the total inductance 54 the higher the efficiency of the circuit in maintaining resonance in the plate and load circuits.

The cathode keying circuit formed by the grid blocking resistor 6 and its shunting switch 7 when opened provides a means for inserting the blocking resistor in the cathode circuit to impress a high negative voltage on the grid and thus prevent the tube from oscillating and leave the characters dark. By intermittently operating the switch 7 the display sign will be caused to flash.

In their operation each of these four circuits is preferably supplied with a high voltage D. C. that operates the tube on the desirable portion of its characteristic curve and upon an initial pulse creates an oscillation in the resonant plate circuit. The field of this oscillation is induced into the secondary or resonant load circuit which is of the same order as that of the primary or resonant plate circuit. In turn the pickup coil of the grid circuit has induced thereon an oscillation of correct phase and magnitude from the resonant load circuit. The measure of the inductance and capacitance of these resonant circuits is preferably inverse to each other which through feed-back is effective on the control grid to sustain the oscillations in resonant circuits.

The addition or subtraction of the characters to the mat 28 in effect change the load of the resonant load circuit which in turn changes its resonant frequency. This change in frequency is reflected through the grid pick coil to maintain the oscillations of the resonant plate circuit in the correct phase and magnitude of the new frequency in the resonant load circuit.

Thus the operating efficiency of the circuit remains substantially unchanged regardless of the change in load of the resonant load circuit. This is one of the important objects of this invention as other types of oscillating circuits must necessarily be returned precisely to suit the load changes.

The principal difference between the present circuit and that of other oscillating circuits resides in the fact that the present circuit requires a tuned or resonant plate circuit and an inductively connected load circuit that is tuned or resonated to the same frequency as that of the resonated plate, and an untuned feed back circuit. Any change in the load is effective in changing the oscillating frequency of the plate and load circuits without materially affecting the resonances of the load circuit. On the other hand the efficiency of operation of the display signs depends upon the automatic change of the frequency through the feed back when the load of the resonant load circuit is changed by adding or taking away letters. This is an undesirable characteristic in other types of oscillating circuits.

By selecting a tuned or resonant plate circuit for oscillating at a frequency less than the physical dimension of the electrodes in the mat 28 the circuit will not produce a standing wave in the mat, which in itself materially reduces radiation of the resonant load frequency.

Again by selecting an oscillating frequency of 75

a low order in the resonant plate and load circuits the capacitance of the resonant plate circuit may be made very large in capacity, which provides a low number of turns and consequently 5 low resistance of the inductance in the resonant plate circuit, resulting in a high Q tank circuit which is substantially devoid of harmonics and which avoids transmitting harmonics to the resonant load circuit. When the harmonics are 10 substantially nil in the plate and load resonant circuits there will be practically no harmonic radiation.

Although the voltage across the electrodes in the mat of the resonant load circuit is high, direct contact across these electrodes by persons 15 merely provides sufficient load, causing the oscillations in the resonant plate and load circuits to die down, thus almost instantly reducing the voltage to zero. Such conditions make this circuit safe for use in places where individuals can 20 handle the display sign without danger, which is also an important object of this invention.

I claim:

1. A display device comprising an electron discharge oscillation generator having an anode, a cathode, and a control grid, a radio frequency step-up transformer including a primary, a secondary and a tertiary winding mounted axially in the order named to provide an efficient low frequency inductive coupling between adjacent windings with the secondary effective in shielding the tertiary winding from the primary winding to prevent high frequency coupling, a resonated anode circuit including said primary, a capacitance sign mat made up of insulating mounted conductors spaced to produce a predetermined capacity and connected with said secondary to produce a resonated load circuit, said resonated anode circuit being tuned to a frequency of the order of said mat and secondary forming said resonated load circuit, a feed back grid circuit including said tertiary winding in an untuned circuit, and sign characters in the form of envelopes containing an ionizable gas at 30 low pressure coupled with said capacitance mat to illuminate the same when the circuit is energized.

2. A display device comprising an electron discharge oscillation generator having an anode, a cathode, and a control grid, a radio frequency step-up auto-connected transformer including a primary, a secondary and a tertiary winding with one end of the primary connected to one end of the secondary and mounted axially in the order named to provide an efficient low frequency inductive coupling between adjacent windings with the secondary effective in shielding the tertiary winding from the primary winding to prevent high frequency coupling, a resonated anode circuit including said primary, a capacitance sign mat made up of insulating mounted conductors spaced to produce a predetermined capacity and connected with said secondary to produce a resonated load circuit, said resonated anode circuit being tuned to a frequency of the order of said mat and secondary forming said resonated load circuit, a feed back grid circuit including said tertiary winding in an untuned circuit and sign characters in the form of envelopes containing an ionizable gas at 40 low pressure coupled with said capacitance mat to illuminate the same when the circuit is energized.

3. A display device comprising an electron discharge oscillation generator having an anode, a cathode, and a control grid, a radio frequency

step-up transformer including a primary, a secondary and a tertiary winding mounted axially in the order named to provide an efficient low frequency inductive coupling between adjacent windings with the secondary effective in shielding the tertiary winding from the primary winding to prevent high frequency coupling, a resonated anode circuit including said primary, a capacitance sign mat made of insulating mounted conductors spaced to produce a predetermined capacity and connected with said secondary to produce a resonated load circuit, said resonated anode circuit being tuned to a frequency of the order of said mat and secondary forming said resonated load circuit, a feed back grid circuit including said tertiary winding in an untuned circuit, sign characters in the form of envelopes containing an ionizable gas at low pressures cou-

pled with said mat to illuminate when the circuit is energized, and an intermittently operated cathode keying circuit to impress a high negative voltage on the grid circuit to suspend operation of said resonated load circuit and flash said characters.

FRANK M. SHOEMAKER.
